M. J. FURLONG

LIQUID DISPENSING APPARATUS

Filed May 25, 1926

By *Watson E. Coleman*
Attorney

UNITED STATES PATENT OFFICE.

MARTIN J. FURLONG, OF HOUSTON, TEXAS.

LIQUID-DISPENSING APPARATUS.

Application filed May 25, 1926. Serial No. 111,578.

This invention relates to certain improvements in liquid dispensing apparatus and it is an object of the invention to provide an apparatus of this kind embodying means whereby the liquid may be dispensed in a predetermined bulk in accordance with the varying positions of the discharge of a container with respect to the high point of the liquid within the container.

10 It is also an object of the invention to provide an apparatus of this kind comprising a receptacle adapted to contain a supply of liquid to be dispensed and which is supported for tilting movement in a vertical direction and wherein a discharge is carried by the upper portion of the receptacle together with variable or adjustable means for limiting the downward swinging movement of the receptacle in accordance with the 20 amount of liquid desired to be dispensed.

The invention consists in the details of construction and in the combination and arrangement of the several parts of my improved liquid dispensing apparatus whereby 25 certain important advantages are attained and the device rendered simpler, less expensive and otherwise more convenient and advantageous for use, as will be hereinafter more fully set forth.

30 The novel features of my invention will hereinafter be definitely claimed.

In order that my invention may be the better understood, I will now proceed to describe the same with reference to the accompanying drawing, wherein:—

35 Figure 1 is an elevational view of a liquid dispensing apparatus constructed in accordance with an embodiment of my invention, a second position of the container being indicated by broken lines;

40 Figure 2 is a view in top plan of the structure as illustrated in Figure 1;

45 Figure 3 is a fragmentary view partly in elevation and partly in section illustrating in detail the means for variably regulating or controlling the downward tilting movement of the receptacle as herein embodied.

50 As disclosed in the accompanying drawing, S denotes a support embodying a pair of upstanding posts 1 each of which being provided at a predetermined point intermediate its end with a slot 2. Each of these slots 2 is adapted to receive an outstanding

trunnion 3 carried by a receptacle R where- 55 by the receptacle is supported for tilting movement.

56 The top 4 of the receptacle R at the peripheral portion thereof and midway of the trunnions 3 is provided with a discharge 60 spout or nozzle 5 extending outwardly beyond the receptacle. The outer end portion of the spout or nozzle 5 is provided on its upper part with a hook member 6 whereby a saddle or shelf 7 may be readily suspended 65 from the spout or nozzle. This saddle 7 is particularly adapted to have rested thereon a container, such as an oil well of a lamp or the like, when it is desired to dispense a small amount of the liquid, such 70 as oil, within the receptacle R when the upper portion of said receptacle is downwardly tilted. By the use of the saddle, such as illustrated in Figure 1 of the drawing, 75 it is assured that such container mounted upon the saddle will be maintained in a proper position irrespective of the extent of downward swinging movement of the upper portion of the receptacle. It will also be understood that if desired this saddle may 80 be of a size larger than that illustrated for use in connection with containers of relatively large capacity.

85 The trunnions 3 are diametrically opposed and are positioned above the longitudinal center of the receptacle R so that the weight of the lower portion of such receptacle together with the weight of the liquid therein will result in the receptacle R normally being maintained in a vertical position, such 90 as is illustrated in full lines in Figure 1.

95 To the upper end portion of one of the posts 1 is attached, as at 8, an end portion of a downwardly disposed arcuate member 9 the outer or lower end portion of which being continued by an inwardly disposed arm 10 attached, as at 11, to the post 1. The arcuate member 9, as is clearly illustrated in Figure 1, is of a length to terminate below the plane of the trunnions 3 so that 100 when the receptacle R is at the limit of its downward swinging movement, as is controlled by the parts to be hereinafter referred to, it will have its top end extending below the horizontal.

105 In the present embodiment of my invention, the member 9 and arm 10 overlie the outer face of the post 1. Secured to the up-

per portion of the post 1 and to the inner face thereof is the upper end portion of a second arcuate member 12 having its periphery on substantially the same curvature as 5 the member 9 and which has its lower portion continued by the inwardly directed arm 14 attached to the inner face of the post 1.

The member 9 is preferably circular in cross section and is surrounded by an eye 10 member 15 carried by a stop arm 16. The eye member 15 permits the stop arm 16 to be readily adjusted along the member 9 or readily swung toward or from the member 12. The arm 16 is also of a length to bridge 15 the space between the members 9 and 12 and to project a desired distance inwardly of the member 12.

The receptacle R is of a capacity to hold 20 a liquid in a predetermined number of liquid measuring units, as for example gallons, and the peripheral marginal portion of the member 12 is provided therealong with the spaced notches or recesses 17. These notches or recesses 17 are spaced apart in requisite 25 computation with respect to the unit capacity of the receptacle R and fractions of such units.

When the arm 16 is selectively engaged 30 within one of such notches or recesses 17 the outer end portion of said arm 16 is in the path of travel of an outstanding member or flange 18 carried by the upper portion of the receptacle R whereby the extent of downward swinging movement of the upper 35 portion of the receptacle is controlled. The notches or recesses 17 are spaced apart in such sequence as to assure a given amount of liquid to discharge from the receptacle R when the upper portion of such receptacle 40 is tilted downwardly a predetermined extent.

In the present embodiment of my invention, the notches or recesses 17 are spaced apart to effect a discharge in gallons. Assuming 45 the receptacle R to be completely filled with liquid and it is desired to dispense a gallon of the liquid, the stop arm 16 is engaged within the uppermost notch or recess 17. The upper portion of the receptacle R is then tilted downwardly until the member or flange 18 comes into contact with said stop arm 16. This will result in a discharge of one gallon of the liquid being discharged through the spout or nozzle 5. 50 When another gallon is desired to be dispensed, the stop arm 16 is engaged within the next notch or recess 17 and so on. It is to be understood at this time that notches 55 may be provided to assure delivery of the liquid within the container in fractions of gallons, such as pints, quarts or otherwise as may be preferred.

Also extending from the eye member 15 60 is a second stop arm 19 in alignment with the first stop arm 16. This arm 19, when the

stop arm 16 is swung upwardly and outwardly away from the member 12, has contact from below with the member 12 to limit the extent of movement of the arm 16 in an outward direction and thus facilitating the operation of adjusting the stop arm 16 along the member 9 as required. 70

The upper portion of the receptacle R has engaged therewith in a conventional manner a bail handle 20 whereby the receptacle R 75 may be readily transported for refilling or handled when being applied with respect to the posts 1. The slot 2 in each of the posts 1 also facilitates the application or removal of the receptacle R. 80

The top 4 at its axial center is also provided with a normally closed filling opening as indicated at 21.

From the foregoing description it is thought to be obvious that a liquid dispensing apparatus constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement 90 and formation of the several parts herein shown in carrying out my invention in practice except as hereinafter claimed. 95

I claim:—

1. A liquid dispensing apparatus comprising 100 a receptacle adapted to contain a supply of liquid, means for supporting said receptacle for vertical tilting movement, a discharge nozzle carried by the upper portion of the receptacle, a stop carried by the supporting means, means for adjusting the stop with respect to the liquid level within the receptacle, and a part carried by the receptacle for contact with the stop to limit the downward tilting movement of the upper portion of the receptacle. 110

2. A liquid dispensing apparatus comprising 115 a receptacle adapted to contain a supply of liquid, means for supporting said receptacle for tilting movement in a vertical direction, a downwardly disposed member positioned adjacent to the receptacle, a stop slidably engaged with the member and selectively adjustable to points therealong, and a part carried by the receptacle for contact with the stop to limit the downward tilting movement of the upper portion of the receptacle. 120

3. A liquid dispensing apparatus comprising 125 a receptacle adapted to contain a supply of liquid, means for supporting said receptacle for tilting movement in a vertical direction, a pair of downwardly disposed members supported adjacent to the receptacle, a stop arm slidably along one of the 130

members and also having swinging movement with respect thereto, the second member being provided with a plurality of spaced notches with which the stop arm is adapted to be selectively engaged, and a part carried by the receptacle for contact with the stop arm when engaged within a notch of the second member to limit the downward swinging movement of the upper portion of the receptacle. In testimony whereof I hereunto affix my signature.

10
